UNITED STATES PATENT OFFICE.

WILLIAM C. METZGER, OF ELMIRA, NEW YORK, ASSIGNOR TO AMERICAN SALES BOOK COMPANY, OF ELMIRA, NEW YORK.

MANIFOLD COPY BOOK OR PAD.

No. 901,935.

Specification of Letters Patent.

Patented Oct. 20, 1908.

Application filed October 22, 1906. Serial No. 339,898.

To all whom it may concern:

Be it known that I, WILLIAM C. METZGER, a citizen of the United States, residing at Elmira, in the county of Chemung and State 5 of New York, have invented certain new and useful Improvements in Manifolding Copy Books or Pads, of which the following is a specification.

This invention relates to improvements 10 in the books or pads now generally used by merchants and others in taking manifold copies of orders, etc.; and the object of my invention is to provide means for manipulating the leaves of the book or pad, without 15 touching the carbon or transfer sheet with the fingers, and yet permit the carbon sheet to completely overlie the leaves of the pad so that entries made on any portion of the original leaves will be transferred to the 20 underlying duplicate leaves.

In the patent to W. F. Beck for improvement in manifold pads and holders, No. 647,934, dated April 24, 1900, there is described a book or pad of this character provided with a carbon sheet which overlies the leaves of the pad concealing the free ends thereof, said sheet being cut away at or near the said free ends to permit the leaves to be grasped and drawn out from under the carbon sheet without touching said sheet. For convenience in handling, this cut-away is located on the right hand side of the book or pad, as it is held for manipulation. It frequently occurs that merchants and others 35 require entries to be made along the extreme right-hand side of the leaves from the top to the bottom thereof, and consequently it is found impracticable in certain such cases to provide the carbon sheet with this cut-away feature, since the cutting away of the carbon will interfere with the transfer of entries, or important parts thereof, from the original to the duplicate leaves. To overcome this difficulty, I provide a carbon sheet 40 for these books or pads arranged substantially in the manner illustrated in the accompanying drawings, in which—

Figure 1 represents a perspective view of a manifolding sales-book embodying my improvement with the carbon sheet overlying the uppermost leaf; Fig. 2, a similar view of the book with the uppermost original leaf drawn out from under the carbon sheet and laid down upon said sheet in position for

writing an order thereon and transferring 55 said order, through the medium of the carbon sheet, to the underlying copy, or duplicate leaf; and Fig. 3, a fragmentary view showing a modification.

Like letters of reference designate like 60 parts in the several views.

The sales-book, as illustrated in the drawings, consists of a pad of leaves A comprising alternating original and duplicate leaves, said leaves being stapled together at one end 65 at B to form a stub, from which the leaves are severed along perforated lines, as indicated at C.

D indicates a cover or holder for the pad, to which the pad may be attached in any desirable manner. In this form of pad the carbon sheet E is fastened either to the holder or to the under side of the pad at the free ends of the leaves, as at F, and folded over said free ends so as to completely over- 75 lie the uppermost leaf.

In order to get at the first underlying leaf without touching the carbon sheet, I make two cuts into the carbon sheet at one side, as at g in Fig. 1, and bend back the portion 80 G between said cuts, thereby forming a flap which, by reason of the crease extending between the inner ends of the cuts, will naturally assume the position shown for it in Fig. 1; thereby permitting the thumb to be in- 85

serted beneath the carbon sheet at this point and placed upon the underlying leaf to draw said leaf out to one side, where it may be grasped between the thumb and finger and drawn back so that the carbon sheet may 90 fall into place upon the next underlying duplicate leaf. The original leaf is then laid down upon the carbon sheet, as shown in Fig. 2, thereby pressing the flap G down upon the duplicate sheet and permitting entries made on the original leaf over said flap to be transferred to the duplicate leaf. When an original leaf has been removed the flap will again spring up into position to enable the next underlying leaf to be grasped. 95 This flap may be formed on the carbon sheet at any point along the edge where the leaves may be readily grasped to manipulate the book, the leaves being more readily manipulated when the flap is located near the free 100 ends of the leaves. Instead of forming the flap by two cuts into the sheet, it may be produced by one cut only, the hinge for the

105

flap being formed by a diagonal crease in the direction in which the leaves are to be withdrawn, as illustrated at G' in Fig. 3.

5 A carbon sheet having a portion thereof at one side, adjacent the free ends of the leaves, cut to form a flap, said flap when raised being adapted to expose a portion of the underlying leaf for manipulating the leaves, substantially as herein described may 10 be applied to any form of book or pad wherein the leaves are so concealed by the carbon sheet as would otherwise render it necessary to handle said sheet in order to manipulate the leaves.

15 What I claim as my invention and desire to secure by Letters-Patent is:

1. The combination, with the leaves of a manifolding book or pad, of a carbon sheet which overlies the leaves, said sheet having

a portion thereof at one side adjacent the 20 free ends of the leaves cut to form a flap, said flap when raised being adapted to expose a portion of the underlying leaf, whereby the leaves may be grasped in manipulating the book without handling the carbon sheet. 25

2. The combination, with the leaves of a manifolding book or pad, of a carbon sheet which overlies the leaves, said sheet being provided at one side with a flap formed by cutting into and creasing the sheet, substantially as and for the purpose set forth. 30

In testimony whereof I have affixed my signature, in presence of two witnesses.

WILLIAM C. METZGER.
